TOOL HOLDING CLAMP

John M. Aiken, 300 E. 9th St., Hastings, Nebr. 68901

Filed May 15, 1972, Ser. No. 253,694

Term of patent 14 years

Int. Cl. D8—08

U.S. Cl. D8—73

FIG. 1

FIG. 2

FIG. 3

FIG. 4

FIG. 5

FIG. 6

FIG. 1 is a side elevational view of the tool holding clamp showing my new design, wherein the broken line disclosures of a wrench and a fragment of a bench are for illustrative purposes only;

FIG. 2 is an enlarged front elevational view thereof;

FIG. 3 is an enlarged side elevational view of the opposite side thereof;

FIG. 4 is an enlarged elevational view thereof;

FIG. 5 is an enlarged top plan view thereof;

FIG. 6 is an enlarged bottom plan view thereof.

I claim:

The ornamental design for a tool holding clamp, substantially as shown and described.
